[57] CLAIM

The ornamental design for a combined pipe and stand therefor, as shown and described.

DESCRIPTION

FIG. 1 is a perspective view of a combined pipe and stand therefor, showing my new design;

FIG. 2 is a front elevational view thereof;

FIG. 3 is a side elevational view thereof;

FIG. 4 is a rear elevational view thereof;

FIG. 5 is a top plan view thereof;

FIG. 6 is a perspective view of the combined pipe and stand therefor, shown with the two elements separated.
